A. TAUB

TRANSMISSION

Filed June 5, 1926

UNITED STATES PATENT OFFICE.

ALEX TAUB, OF DETROIT, MICHIGAN.

TRANSMISSION.

Application filed June 5, 1926. Serial No. 113,919.

The present invention relates to power transmitting mechanism particularly for toy vehicles such as are adapted to be propelled by the occupant through the actuation of 5 pedals.

Among the objects of the invention is the production of a simple, cheap and efficient device which may be easily and economically made and assembled, and which will not 10 easily get out of order.

Another object is a device of the kind mentioned having change speed means.

With these and other objects in view as will 15 readily appear upon reference to the following description, the invention consists in the means and mechanism illustrated in the accompanying drawing and in such modifications and variations thereof as will come 20 within the scope of the claims hereunto appended.

In the drawing:

Fig. 1 is a horizontal section through the mechanism.

Fig. 2 is a vertical section on the line 2—2 25 of Fig. 1.

As indicated, a preferred embodiment of the invention consists in a power transmission for example, for a toy automobile, the drive mechanism being shown as mounted upon a 30 frame work of which 10 indicates one of the side frame members having a bearing 11 for a "live" rear axle 12 to which is fixed wheel 13. The front end of member 10 is secured to cross member 14 of the frame and the front axle 35 (not shown) may be secured in a convenient manner to this member.

Extending longitudinally and located centrally of the frame is a sub-frame having two side members 20 and 21 which extend from 40 cross member 14 to beyond the rear axle 12, of these, the member 21 has its rearward end extended vertically of the assembly and formed into a cup shaped portion 22 serving as a gear case, being provided centrally of the cup with a bearing 23 for axle 12. The member 20 is 45 also widened at its rear end and serves as a cover 24 for the gear case, and is provided with axle bearing 25.

Within the case, thus formed, and keyed to 50 axle 12 is a combination compound face gear and brake drum 30 consisting of a drum member 31, preferably radially ribbed as at 32, having secured to its outer web face a plural-

ity of toothed rings 33 and 34. Of these the ring 33 will preferably consist of an annular 55 sheet metal channel having gear teeth cut in its flanges. Ring 33 is preferably made by stamping out a flat ring having teeth on its inner and outer peripheries and then die forming to the shape indicated in the drawing. Of course, in cutting the ring, allowance 60 will be made for the deformation produced in the die forming.

The ring 34, in the design illustrated, will 65 be similar to ring 33, except that it will have only one row of teeth.

Ring 33 will be secured, as by rivetting, to the outer edge of the drum web and ring 34 will be secured in a similar manner near the center and preferably to a flanged hub 35 also 70 secured to the web and serving to furnish means for keying the drum and gears to the axle 12.

Within the gear case and secured to the 75 cover portion 24 is a U-shaped piece 36 provided with a passage in its central portion for axle 12 and also with a bearing 37 in one of its legs for the end of drive shaft 40. This shaft 40 extends from near axle 12 to near the front of the subframe 20—21 and is driven 80 by suitable means to be described later.

Upon the rear portion of shaft 40 are mounted loosely gears 41, 42, and 43, each having welded thereto flanged sleeves 44 there being two of these for each gear forming a spacing hub therefor. Gears 41, 42, and 43 are prevented from moving forward on shaft 40 by means of a collar 45. These three gears are so spaced as to be in constant mesh with the corresponding teeth on rings 33 and 34, and each is provided with a slot 46 on its inner periphery. Shaft 40 is also slotted longitudinally as at 47 and in this slot lies a spring 48 secured at one end to a collar 49 slidable on shaft 40. The other end of spring 95 48 is bent upwardly as shown in Fig. 1 and is adapted to press outwardly into one of the slots 46 in one of the gears 41, 42, and 43, thereby keying the particular gear to the shaft. Collar 49 is grooved externally as at 100 50 and in this groove lies a shifter fork 51 carried by a rod 52 extending forward to a suitably located hand or foot lever (not shown). When the collar 49 is moved it will 105 carry with it the spring 48 and pick up one of the gears 41, 42, and 43, depending of course

on its position. The drawing shows the spring to be engaged in the slot of gear 41. As the three gears on the shaft 40 are of the same size and the gears on rings 33 and 34 different sizes, this means offers several driving speeds for the vehicle.

The front end of shaft 40 carries a gear 60 fixed to it for example by pins 60^a, a short distance from the end, and the shaft 40 has a bearing in a second U-shaped piece 61 similar to member 36. Piece 61 is secured to sub-frame member 21 and through it passes a shaft 62 to the ends of which are secured pedals 63. Keyed to shaft 62 is a hub piece 64, similar to hub 35, to which is secured a formed sheet metal ring gear 65, similar to ring 34. Gear 65 meshes with gear 60 and serves to transmit torque from the pedals to shaft 40 and therefore to the shaft 12.

20 The brake drum 31 will be provided with a suitable brake band 70 anchored to the frame as at 71 and actuated in suitable fashion through a hand or foot lever.

It will be noted that gears 41, 42, 43, and 25 60 are identical in form and size and each is made up of the stamped gear and sleeve hub members. It will also be noted that the ring gears 34 and 65 are identical as are the two hub members 35 and 64 and the two U-shaped 30 members 36 and 61.

This duplication and consequent interchangeability makes for cheaper and simpler manufacture and assembly of the device and is a decided advantage over known structures.

35 In addition to this simplification the structure as used in a toy vehicle furnishes an over-drive ratio, a normal drive ratio and an under-drive ratio, thus permitting the vehicle to be operated by a small child on the 40 under-drive ratio or to be operated normally or at high speed on the other two ratios. For example, with a gear ratio at the pedal of 1½:1 and 1:3 at the rear axle, the drive is 1:1½ for slow speed. With the same ratio at 45 the pedals and 1:1½ at the axle the drive is 1:1 or normal. With the same ratio at the pedals and 1:1 at the axle the drive is 1½ to 1 or high speed ratio.

Having now described the invention and 50 the preferred form of embodiment thereof, it should be noted that the said invention is not to be limited to the specific details herein set forth but only by the scope of the claims which follow.

55 I claim:—

1. Driving mechanism for a toy vehicle consisting of a pedal driven lateral shaft, a longitudinal shaft, a face gear fixed on said lateral shaft meshing with a spur gear fixed 60 to the longitudinal shaft, a plurality of other spur gears identical with the first mentioned one and loosely mounted on said longitudinal

shaft, a driving axle for the vehicle, a compound face gear meshing with said plurality of spur gears and secured to said driving axle, 65 and means for fixing at will to said longitudinal shaft a selected one of said plurality of spur gears.

2. In speed selecting mechanism for toy vehicles, a compound face gear secured to a 70 driving axle for the vehicle, a drive shaft parallel to the face of said gear and having a plurality of drive pinions loosely mounted thereon, each pinion having an internal slot, a longitudinal slot in said drive shaft and extending through said pinions, a slid able collar on said shaft and a spring finger secured to said collar and lying in said longitudinal slot, said finger having a bent portion at its free end adapted to spring out into one of the 80 pinion slots and thereby fix said pinion to said shaft in driving relation.

3. Drive mechanism for a toy vehicle having a driving axle, said mechanism including a sub-frame secured to the body frame, a laterally extending shaft carrying pedals at its extremities supported in said sub-frame, a ring gear fixed on said shaft, a U-shaped member fixed to one side of the sub-frame and supported on said shaft, a longitudinally extending drive shaft provided with a bearing in said U-shaped member and having fixed thereon a pinion meshing with said ring gear, a second U-shaped member like the first fixed to the sub-frame and supported at its other end on the driving axle for the vehicle, said second member providing a bearing for the other end of the drive shaft, a ring gear fixed on said axle, and a pinion on said drive shaft meshing with the 90 latter ring gear.

4. Drive mechanism for a toy vehicle having a driving axle, said mechanism including a sub-frame secured to the body frame, a laterally extending shaft carrying pedals at 105 its extremities supported in said sub-frame, a ring gear fixed on said shaft, a U-shaped member fixed to one side of the sub-frame and supported on said shaft, a longitudinally extending drive shaft provided with a bearing in said U-shaped member and having fixed thereon a pinion meshing with said ring gear, a second U-shaped member like the first fixed to the sub-frame and supported at its other end on the driving axle for the vehicle, said second member providing a bearing for the 110 other end of the drive shaft, a compound face gear fixed on said axle, a plurality of pinions loosely mounted on said drive shaft and meshing with said compound face gear, and means for selecting and fixing any one of said loose pinions to said drive shaft at will.

ALEX TAUB.
